GOLF CLUB

Allan E. Lard, Washington, D. C.

Application March 13, 1934, Serial No. 715,322

7 Claims. (Cl. 273—77)

This invention relates to golf clubs and particularly to means providing for the color ornamentation of golf shafts and the preservation thereof against mutilation.

5 As is well known, a plurality or set of golf clubs is customarily carried in a bag or the like, in a single compartment thereof. The clubs when being carried in the bag therefore may jostle against each other; and when the bag is laid down or dropped upon the ground, the head of a short club, such as an iron club for example, may impinge upon the shaft of another club; and when one club is withdrawn from the bag, the shaft of the club being withdrawn may drag over the heads of other clubs in the bag.

10 It has been proposed to ornament the shafts of golf clubs by ornamental surface finish of the shaft or by applying color thereto, etc., but because the clubs impinge on each other and may abrasively drag over each other as above referred to, such ornamentation is quickly mutilated when the clubs are put in use and soon renders them more unsightly than if the ornamentation had not been applied.

15 It is an object of the present invention to provide a golf shaft having a construction adapted to improved color ornamentation thereof and to effect protection of the ornamentation from mutilation which may occur as above described.

20 Other objects will be apparent to those skilled in the art to which my invention appertains.

25 My invention is fully disclosed in the following description taken in connection with the accompanying drawing, in which:

30 Fig. 1 is an elevational view of a golf club embodying my invention;

35 Fig. 2 is an elevational view of the shaft alone of Fig. 1, the transverse dimensions of the shaft of this figure being increased for clearness;

40 Fig. 3 is a view illustrating a mode of operation of my invention;

45 Fig. 4 is a fragmentary view similar to a part of Fig. 3 drawn to a larger scale;

Fig. 5 is a cross-sectional view taken from the plane 5—5 of Fig. 4, the view being also taken approximately from the plane 5—5 of Fig. 2;

50 Fig. 6 is a cross-sectional view similar to Fig. 5 but taken from the plane 6—6 of Fig. 2;

Fig. 7 is a cross-sectional view taken from the plane 7—7 of Fig. 2;

55 Fig. 8 is a fragmentary view to a greatly increased scale of a part of Fig. 5 or of Fig. 6 or of Fig. 7;

Fig. 9 is a fragmentary cross-sectional view

generally similar to a part of Fig. 5 and illustrating a step of process which I may employ;

Fig. 10 is a view generally similar to Fig. 2 but illustrating a modification;

Fig. 11 is a fragmentary cross-sectional view of a shaft embodying my invention and illustrating a still further modification.

As will appear hereinafter, a golf club or a golf shaft embodying my invention may be made from wood, or metal, or other suitable materials. However, in the instant application I have illustrated and will describe my invention as embodied in a tubular shaft of metal such as steel. Such a shaft is indicated generally at 1 in the drawing.

Extending longitudinally of the shaft 1 is a plurality, such for example as eight, of grooves 2—2 which, in the particular embodiment illustrated, are formed by making longitudinally extending indentations in the wall of the tubular shaft.

The lower end of the shaft 1 is inserted into the hosel 3 of a golf club head 4; and the other end is provided with a handle grip 5. The shaft may taper toward the club head 4.

Any suitable apparatus and method may be employed to form the grooves 2—2 in the wall of the tubular shaft. The longitudinally extending intermediate portions 6—6 between the grooves 2—2 may be externally finished by any suitable method and means, but are preferably polished to present the color of the metal. A stripe of paint, lacquer, duco or the like is then applied upon the wall of each groove extending longitudinally thereover and preferably of a color contrasting with that of the intermediate portions 6—6. The color stripe is indicated at 7 in Fig. 8 in cross-section greatly magnified.

Preferably the shaft, or the intermediate portions 6—6 thereof, is chromium-plated and polished and the grooves are colored lavender or purple. Or, the shaft may be parkerized and then given a coat of black lacquer in which case the grooves may be colored white.

The blades 4 of different clubs of a set may be variously shaped. Some surfaces thereof may be straight, some curved irregularly and some circular and the corners and edge portions may have angles more or less acute as shown for the blades 9 and 28 of Fig. 5; and 29 of Fig. 4 and 4 of Fig. 3.

As will be readily understood, therefore, if the stripe or other configuration of color ornamentation were applied to outer portions of the shaft, such for example as to the intermediate longitudinally extending portions 6—6, it very quickly would become mutilated by the impact of the

head of one club on the shaft of another club when carried in the golf bag, somewhat as illustrated for example in Fig. 3 wherein, in a golf bag 8, the head 4 of one club impinges upon the shaft 1 of another club; or would be mutilated by the abrasive action between the head of one club and the shaft of another club when the said other club were withdrawn from the bag, for example, referring to Fig. 3, when the shaft 1 is withdrawn from the bag and drags with abrasive action upon the adjacent portions of the head 4 of the other club.

In the practice of my invention, the mutilation of the color ornamentation is prevented. To this end, the width of the grooves 2-2 is restricted and the depth thereof is extended so that no portion of the head of one club can enter the groove of another club sufficiently far to contact the wall thereof and mutilate the color stripe therein. In Fig. 5 is indicated the engagement of the outer end or toe of an iron head 28 with a shaft to illustrate the degree of restriction of the width of the grooves, and in the same figure is indicated the engagement with a shaft of a corner edge or relatively sharp angle of an iron head 29, and illustrating the degree of extension of the groove depth and demonstrating that although the corner or edge of said head may penetrate into a groove 2, it cannot contact the wall thereof or mutilate the color stripe thereon.

It is the iron clubs, particularly the less lofted iron clubs such as the putter, that are most liable to enter a groove and mutilate the color stripe; and if the grooves are sufficiently narrow and deep, as stated, to prevent mutilation by these clubs, they will prevent mutilation by all other clubs. For this reason only iron head clubs have been illustrated and described. But it will be clear that my invention may be practiced with clubs having heads of wood.

In applying the color stripe to the grooves, the paint, duco, lacquer or the like may be applied with a brush of suitable size to paint the stripe with well defined lateral edges. Or, if preferred, the method partly illustrated in Fig. 9 may be employed; the groove may be painted with a brush without particular care to give the stripe clean-cut lateral edges and the paint may in fact extend to the generally cylindrical portions of the shaft adjacent the sides of the groove. Then while the paint is still wet, a tool indicated at 12 having the form of a golf club head and particularly having an edge portion 13 the angle of which is at least as acute as that of any angle 55 or edge on the club heads of a set of clubs, is covered with a fabric cover or sock 14. The fabric covered edge 13 is then wet with turpentine and projected into the groove 2 as far as it will go and is then drawn longitudinally of the groove 60 to wipe off all of the paint at the radially outer terminations of the groove. The color stripe will thereby be given well defined lateral edges, giving it a neat appearance and at the same time the color stripe is limited to those portions of the 65 groove which cannot possibly be reached by any portion of any of the club heads of the set.

In the form of Figs. 1 to 8 inclusive, the grooves 2-2 are substantially of uniform depth and width throughout the length of the shaft. In Fig. 10 I have shown a modification in which the grooves taper in width or in width and depth toward the small end of the shaft. If desired furthermore, as shown in Fig. 10, the grooves may be formed only in the intermediate portion of the shaft 70 starting at a point adjacent the handle grip por-

tion and terminating at or somewhat above the hosel.

In Fig. 11 is indicated a further modification. It has been proposed to cover metal golf shafts with a layer of material such as celluloid. This may be done either by dipping the shaft in lacquer or in fluid pyroxylin and allowing the coating thus applied to harden. A shaft having grooves therein as illustrated and described in connection with Figs. 2 or 10 may be coated with celluloid or a hard material of pyroxylin base or the like, and the grooves in the shaft, now coated with the celluloid layer, may be painted with a duco or other color stripe.

As another means and method of applying a 15 layer of celluloid or the like to the shaft, a tube of celluloid may be formed substantially of the size and shape of the exterior of the shaft and after heating the same in hot water it may be telescoped over the shaft and allowed to cool 20 and shrink thereon and to adhere tightly and permanently thereto. Grooves may be previously formed in the celluloid shell thus provided to register and nest with the grooves in the shaft; or, the grooves may be formed simultaneously 25 in the shell and shaft after the shell has been applied. In either case, the grooves may be painted with a color stripe as above described, preferably using duco or like paint having a pyroxylin base.

In Fig. 11 is illustrated in cross-section the appearance of a shaft 15 having grooves 16 therein and a celluloid or the like shell 17 thereon having corresponding grooves 18 nested with the grooves 16 of the shaft. The color characteristic of the grooves 18 is indicated by the difference in cross-hatching of the grooved portions 18 of the shell 17.

My invention is not limited to any specific means or method of producing the grooves in 40 the shaft. Where tubular steel shafts are used, the method and means of making the known and in some cases commercial grooved shafts may be employed. If it be desired to similarly groove a shaft of wood or other material, the grooves 45 may be formed therein by any well known method.

Neither is my invention limited to a plurality of color striped grooves; nor to a color striped groove or grooves extending longitudinally of 50 the shaft.

In other respects also my invention is not limited to the exact details illustrated and described. Many changes and modifications may be made within the scope and spirit of my invention without departing therefrom as set forth in the appended claims.

I claim:

1. In a golf club, a shaft having a head thereon, the shaft having a longitudinally extending 60 outwardly open groove in the outer surface thereof of having a color stripe of paint or the like extending longitudinally along and in the groove, the groove being of restricted substantially constant width and extended substantially constant 65 depth whereby when the head of any club is disposed adjacent to the shaft of said club with the shafts of both clubs extending generally in the same direction, all portions of the said head are prevented from entering the groove to engage and mutilate the shaft groove stripe of the said club.

2. In a golf club, a shaft having a head thereon, the shaft having a plurality of longitudinally extending outwardly open grooves in the outer 75

surface thereof, a color stripe of paint or the like extending longitudinally along and in each groove, the grooves being of restricted substantially constant width and extended substantially 5 constant depth whereby when the head of any club is disposed adjacent the shaft of said club with the shafts of both clubs extending generally in the same direction, all portions of the said head are prevented from entering any of 10 the grooves of the said club to engage and mutilate the shaft groove stripes thereof.

3. In a golf club, a shaft having a handle grip supporting portion on one end and a club head supporting portion on the other end, and a groove 15 in the outer surface of the shaft of a width less than the thickness of an iron type club and of a depth substantially corresponding to its width and a color stripe of paint or the like in the groove.

4. In a golf club, a shaft having a handle grip supporting portion on one end and a club head supporting portion on the other end, and a longitudinally extending groove in the outer surface of the shaft of a width less than the thickness of an iron type club head and of a depth substantially corresponding to its width and a color stripe 20 of paint or the like in the groove.

5. In a golf club, a shaft having a head thereon, the shaft having a longitudinally extending outwardly open groove in the outer surface thereof of having a color stripe of paint or the like in 25

the groove, the groove being of substantially constant restricted width and substantially constant extended depth whereby when the head of any club is disposed adjacent to the shaft of said club with the shafts of both clubs extending generally in the same direction, all portions of the said head are prevented from entering the groove to engage and mutilate the shaft groove stripe of the said club.

6. In a golf club, a shaft having a head thereon, the shaft having a plurality of longitudinally extending outwardly open grooves in the outer surface thereof, a color stripe of paint or the like in each groove, the grooves being of substantially constant restricted width and substantially constant extended depth whereby when the head of any club is disposed adjacent the shaft of said club with the shafts of both clubs extending generally in the same direction, all portions of the said head are prevented from entering any 20 of the grooves of the said club to engage and mutilate the shaft groove stripes thereof.

7. A shaft for golf clubs, formed to have longitudinally extending outwardly presented recesses and an inlaid decorative stripe applied to the inner wall of the recesses, the recesses being of a width and depth as to protectively guard against damage to said stripe by the heads of other golf clubs carried in a golf bag adjacent to said shaft.
